JACKET OR SIMILAR ARTICLE

Kunisaku Ino, 347 Grant Ave., San Francisco, Calif.

Filed Aug. 21, 1961, Ser. No. 66,425

Term of patent 14 years

(Cl. D3—4)

FIG. 1 is a front view of a jacket or similar article embodying my new design; and

FIG. 2 is a rear view of the same.

The sleeve of the jacket or similar article is shown folded over for convenience of illustration.

I claim:

The ornamental design for a jacket or similar article, substantially as shown and described.
